Alfred C. Hill,
BY *J. Stanley Borch*

ATTORNEY.

UNITED STATES PATENT OFFICE

ALFRED C. HILL, OF VERNON, TEXAS

DISPLAY STAND

Application filed May 18, 1929. Serial No. 364,283.

The present invention relates to improvements in display stands and has reference more particularly to a device adapted to be placed on a counter in a store or other similar place for displaying merchandise.

One of the important objects of the present invention is to provide a display stand wherein the same includes angularly disposed trays for receiving and displaying the merchandise, a removable placard having suitable indicia printed or otherwise arranged thereon being supported across the top of the display stand.

A further object is to provide a display stand of the above-mentioned character wherein the parts are so arranged and assembled as to provide a relatively strong construction, said display stand being further adapted to present a neat appearance when placed on a counter or show case.

Another object is to provide a display stand of the above-mentioned character wherein the same is constructed in such a manner as to permit access to the trays from either side.

A still further object is to provide a display stand of the above-mentioned character that can be constructed at a very low cost and which will at all times be positive and efficient in carrying out the purposes for which it is designed.

Other objects and advantages of the invention will become apparent from the following description when taken in connection with the accompanying drawings.

In the accompanying drawings wherein like reference characters indicate corresponding parts throughout the same;

Figure 1 is a side elevation of the display stand embodying my invention.

Figure 2 is a top plan view thereof.

Figure 3 is an end elevation.

Figure 4 is a vertical sectional view taken approximately on the line 4—4 of Figure 1; and

Figure 5 is a longitudinal vertical sectional view taken substantially on the line 5—5 of Figure 2 looking in the direction of the arrows.

In the drawings wherein for the purpose

of illustration is shown the preferred embodiment of my invention, the numeral 1 designates generally my improved display stand, the same comprising a pair of parallel spaced transversely disposed base members 55 or feet 2 and 3 respectively. Each base member comprises a rectangularly shaped piece of wood, the upper edge of which is inclined gradually from the central portion thereof toward the respective ends, said inclined portions being denoted by the numeral 4 with reference more particularly to Figures 3 and 4 of the drawings. Upon referring to the aforementioned figures, it will be further noted that the ends of each wooden bar constituting the base or feet converge gradually toward the lower straight edge of said bar.

The display stand further includes the provision of a pair of vertically disposed standards 5 and 6 respectively and the lower edge portion of each standard is cut away at its inner face to provide a shoulder 7. The lower end portions of the standards are secured by any appropriate fastening means to the outer faces of the central portions of the respective bases or feet so that the shoulder 7 will abut against the straight upper edge of the central portion of each base or foot as suggested very clearly in Figures 4 and 5. The upper end of each standard is formed with a longitudinally extending slit 8 for a purpose to be presently described. The inner face of each standard is also cut out as indicated at 9 in the intermediate portion thereof to accommodate a transversely disposed arm. The arm that is associated with the standard 5 is denoted by the reference character 10 while the arm that fits within the cut out portion formed in the opposite standard 6 is denoted by the numeral 11 80 and in Figure 5 of the drawings, there is clearly illustrated the relationship of the transversely disposed arms with respect to the vertical standards.

The arms 10 and 11 are of a length less than that of the feet or base members 2 and 3 but the upper edge of each cross arm is inclined gradually from the central portion thereof toward the respective ends and the inclined portions are indicated at 12. Also 100

the ends of each cross arm converge gradually toward the lower straight edge thereof. Any appropriate fastening means may be driven through the standards of the respective cross arms to provide a rigid structure.

5 Disposed across the inclined upper edges of the feet or base members 2 and 3 on one side of the standards 5 and 6 is the angularly disposed tray 13. A similar tray 14 extends across the inclined upper edges of said base or feet members on the opposite sides of the standards.

10 Smaller angularly disposed trays 15 and 16 respectively are arranged across the inclined upper edges of the cross arms 10 and 11 on the opposite sides of the vertical standards 5 and 6 as clearly shown in the drawings.

15 Each of the aforementioned trays include 20 a bottom board 17 and an upstanding rim 18 around the outer edges of the board.

25 The inner opposed edges of the boards of each pair of trays are disposed in abutting relation and the merchandise to be displayed 30 is placed in the upper and lower trays and as the lower trays extend outwardly beyond the outer edges of the upper trays, access to the several trays may be readily and easily had in order to remove the contents of the 35 various trays therefrom from either side of the display stand.

40 A placard 19 bearing any suitable advertising indicia or other printed matter is disposed across the upper ends of the standards 35 and the respective ends of the placard are removably fitted in the slots 8 provided therefor in the upper ends of the standards.

45 A display stand of the above-mentioned character can be constructed at a very low cost and may be placed upon a counter or show case for displaying merchandise contained within the trays in a conspicuous manner. Furthermore by arranging the parts in the manner as shown and described, the 50 display stand will be rendered strong and durable.

55 While I have shown the preferred embodiment of my invention, it is to be understood that minor changes in the size, shape and 60 arrangement of parts may be resorted to without departing from the spirit of the invention or the scope of the appended claims.

What I claim is:

65 1. In a display stand, a pair of spaced base members, standards secured at their lower ends to the central portions of the respective base members on the outer faces thereof, cross arms secured to the intermediate portions of the standards, the upper edges of the base members and the cross arms being respectively inclined gradually from the central portion to the outer ends thereof, and angularly disposed trays arranged across the inclined upper edges of the

base members and the cross arms respectively on opposite sides of the standards.

70 2. In a display stand, a pair of spaced base members, a pair of standards secured at their lower ends to the outer faces of the respective base members at the intermediate portions thereof, the inner face of each standard being cut out to form a shoulder for abutting engagement with the upper edge of the respective base member, the inner face of each standard being cut out at its intermediate portion, a cross arm secured at its central portion in the intermediate cut out portion of each standard, trays secured across the upper edges of the base members on opposite sides of the standards, and additional trays secured across the upper edges of the arms on opposite sides of the standards.

75 In testimony whereof I affix my signature.
